LAUNDRY MACHINE

Lurelle V. A. Guild, Noroton, Conn., assignor to Westinghouse Electric Corporation, a corporation of Pennsylvania

Application May 1, 1953, Serial No. 24,788

Term of patent 14 years

(Cl. D49—3)

To all whom it may concern:

Be it known that I, Lurelle V. A. Guild, a citizen of the United States, residing at Noroton, in the county of Fairfield and State of Connecticut, have invented a new, original, and ornamental Design for a Laundry Machine, of which the following is a specification, reference being had to the accompanying drawing, forming a part thereof.

The single figure of the drawing is a perspective view of a laundry machine embodying my new design.

The side of the laundry machine not shown is similar in appearance to the side in view.

The characteristic features of the design for the laundry

machine disclosed reside in the upper centrally disposed front door having the configuration shown.

I claim:

The ornamental design for a laundry machine, substantially as shown and described.
